(57) CLAIM

The ornamental design for a rotating media player clock radio, shown and described.

DESCRIPTION

FIG. 1 is a front, side perspective view of a rotating media player clock radio showing my new design;

FIG. 2 is a front view thereof;

FIG. 3 is a rear view thereof;

FIG. 4 is a top view thereof;

FIG. 5 is a bottom view thereof;

FIG. 6 is a side view thereof, the opposite side view being a mirror image;

FIG. 7 is a cross-sectional view along line 7-7 in FIG. 2;

FIG. 8 is a cross-sectional view along line 8-8 in FIG. 2.

FIG. 9 is a cross-sectional view along line 9-9 in FIG. 2; and,

FIG. 10 is a cross-sectional view along line 10-10 in FIG. 2.

The broken lines in the drawings illustrate environmental material that forms no part of the claimed design.
